UNITED STATES PATENT OFFICE

133,600

DESIGN FOR A DRESS

Henry Salow, Philadelphia, Pa.

Application July 29, 1942, Serial No. 107,740

Term of patent 3½ years

To all whom it may concern:

Be it known that I, Henry Salow, a citizen of the United States of America, residing in Philadelphia, county of Philadelphia, and State of Pennsylvania, have invented a new, original, and Ornamental Design for a Dress, of which the following is a specification, reference being had to the accompanying drawing, forming part thereof.

Fig. 1 is a front view of a dress showing my new design.

Fig. 2 is a rear view thereof.

I claim:

The ornamental design for a dress, substantially as shown.

HENRY SALOW.
